UNITED STATES PATENT OFFICE.

PHILLIP J. MUTCH, OF HOBOKEN, PENNSYLVANIA.

JARDINIÈRE-STAND.

1,300,635.

Specification of Letters Patent.

Patented Apr. 15, 1919.

Application filed February 18, 1918. Serial No. 217,941.

To all whom it may concern:

Be it known that I, PHILLIP J. MUTCHE, a citizen of the United States, residing at Hoboken, in the county of Allegheny and State 5 of Pennsylvania, have invented a new and useful Jardinière-Stand, of which the following is a specification.

The device forming the subject matter of this application is a jardinière stand, and 10 the invention aims to provide a structure of this kind which, when not in use, may be folded up into small compass, novel means being provided for retaining a shelf on which the jardinière is supported, novel 15 means being provided for holding the radial members of the pedestal portion of the stand in proper relation to each other, and the construction being such that the stand will not alter its shape or collapse when set up 20 for use.

It is within the province of the disclosure to improve generally and to enhance the utility of devices of that type to which the present invention appertains.

With the above and other objects in view 25 which will appear as the description proceeds, the invention resides in the combination and arrangement of parts and in the details of construction hereinafter described 30 and claimed, it being understood that changes in the precise embodiment of the invention herein disclosed can be made within the scope of what is claimed without departing from the spirit of the invention.

In the accompanying drawing:—

Figure 1 is an elevation of the stand;

Fig. 2 is a top plan thereof;

Fig. 3 is a transverse section on the line 3—3 of Fig. 1;

Fig. 4 is a fragmental top plan showing 40 the upper edges of certain of the radial members;

Fig. 5 is an elevation showing one of the 45 radial members and a part of the shelf, portions being in section;

Fig. 6 is an elevation showing the inner edges of some of the radial members and illustrating the latch mechanism.

The stand forming the subject matter of 50 this application comprises a pedestal 1 made of a plurality of plate like radial members 2 each including a body 3 having an up-standing arm 4, the inner edges of the arms being supplied with shoulders 5, the bodies 55 3 including outstanding supporting feet 6. The inner edges of the bodies 3 of the radial

members 2 are hingedly connected in any suitable manner. If desired, a strip of canvas or other flexible material denoted by the numeral 7 may be cemented to the inner 60 edges of the body 3 and be held thereto by securing elements 8. Two adjacent members 2 are, of course, not connected with each other by means of the strip 7, the construction being such that, when the device is not 65 in use, the radial members 2 may be folded into contact, so as to occupy but little room. The arms 4 define a central space 9, and when the members 2 are radially disposed, the inner edges of the bodies 3 of the radial 70 members fashion a central space 10 into which is inserted a former 11 having a shoulder or flange 12, which, coacting the upper edges of the bodies 3 limits the downward movement of the former. The former 75 serves to position the inner edges of the bodies 3 with respect to each other, and to hold the radial members 2 against movement.

The adjacent radial members 2 which are 80 not connected by means of the hinge strip 7 may be united in any suitable way. For instance, one of these members may be supplied upon its upper edge with a spring latch 14 having a depending end 15. The 85 other of the adjoining members may be supplied with a transverse keeper 16 having a projection 17 coacting with the end 15 of the latch 14. When it is desired to collapse the stand, the free inner end of the latch 14 90 may be raised, thus disengaging the element 15 from behind the projection 17 on the keeper 16, whereupon the radial members 2 may be folded together as aforesaid.

A shelf 18 is disposed in the central space 95 9 defined by the arms 4 and is supported on the shoulders 5, the shelf having peripheral notches 19 wherein the inner edges of the arms 4 are received. Any suitable means may be provided for preventing the shelf 100 18 from moving upwardly and for holding the shelf in place on the shoulders 5. With this end in view, casings 20 may be inserted into the inner edges of certain of the arms 4, above the shoulders 5, detents 21 being 105 mounted to slide in the casings, the detents being advanced by means of the springs 22 disposed within the casings, the projecting ends of the detents coacting with the upper surface of the shelf 18, to prevent the shelf 110 from moving upwardly.

When it is desired to collapse the stand,

the detents 21 are pushed inwardly, the shelf 18 is raised out of engagement with the arms 4, and the latch 14 is disconnected from the keeper 16, whereupon the radial members 2 may be folded together on the hinges formed by the strip 7.

Having thus described the invention, what is claimed is:

A jardinière stand comprising a pedestal made up of a plurality of radial members each including a body and an arm upstanding from the body, the arms coöperating to form a central space and being provided on their inner edges with shoulders, the inner edges of the bodies coöperating to form a second central space; a shelf supported on the shoulders and disposed within the central space defined by the arms; a former in the central space defined by the inner edge

of the bodies, the former being provided with a shoulder coacting with the upper edges of the bodies to limit the downward movement of the follower; means for hingedly connecting the inner edges of the bodies, the bodies of two adjacent members being free to permit the radial members to be folded together; and a latch forming a releasable connection between said adjacent free members to hold all of the radial members above the former.

In testimony that I claim the foregoing as my own, I have hereto affixed my signature in the presence of two witnesses.

PHILLIP J. MUTCH.
